METHOD OF GRINDING AND POLISHING
GEM FACETSGregor H. Rakowitzky, Brooklyn, N. Y., assignor
of one-half to Joseph Alster, New York, N. Y.

Application March 31, 1944, Serial No. 528,884

1 Claim. (Cl. 51—283)

1

This invention relates to a method for grinding and polishing the facets of diamonds and other gems for use in the lapidary art and in the technical and industrial arts.

One object of the invention is to provide an improved grinding or polishing method whereby better results are obtained in less time without impairing the grinding surface.

Another object is the provision of a machine of improved construction and operation, and still another object is to provide gem holders or dopps of such construction that the gems are handled with greater accuracy and security and without the aid of cements, adhesives, or similar anchoring agents.

With these and other objects in view my invention consists in the improved method and in the improved construction and arrangement of parts of the machine as hereinafter more fully described, by way of illustration or example and with reference to the accompanying drawings whereon:

Fig. 1 is a side view of a gem;

Fig. 2 is a diagrammatic plan view showing the grinding surface and the path of the gem;

Fig. 3 is a front view of the machine;

Fig. 4 is a detail view, partly in section, showing part of the driving gear for the grinder;

Fig. 5 is a detail view showing the opposite side of the gem carrier of Fig. 3;

Fig. 6 shows a part of said carrier as seen in the direction of the arrow 6, Fig. 3;

Fig. 7 is a part section and part side view of the gem holder or dop for use while grinding the base or pavilion facets;

Fig. 8 is a face view of the collar or index disc for use while grinding said facets.

In carrying out the improved method according to this invention, a grinding table 15, Fig. 2, is rotated at high speed about a vertical axis 18 while the gem is mounted in a holder carried at an angle corresponding to the angle of the facet to be ground and is caused to move continuously in a circular path 19 about a vertical axis so spaced from the axis of the table that the gem which contacts the grinding surface of the table is constantly changing its position with respect to the axis of the table and at the same time is constantly turning so that the grinding action of the table surface is applied to the gem at constantly changing angles with respect to the "grain" of the gem. As the table and the gem are thus independently rotated—the former at a high and the latter at a relatively low angular speed—the portion of the table 15 engaged by

the gem forms an annular track defined by the concentric lines 16, 17 which are of course concentric to the table axis 18, and the distance between the axis 18 and the line 16 is somewhat greater than the distance between the lines 16, 17, so that the relative speeds of the contacting surfaces of the table and gem do not materially change. In the preferred arrangement, the gem is moved in a clockwise direction in the path 19 while the table 15 also rotates clockwise so that the relative speeds of the parts at the points of contact are less variable. It has been found that satisfactory results are obtained with the table 15 making thirty or more revolutions to each revolution of the gem.

In operation the track between the lines 16, 17 is surfaced with oil and diamond dust or other abrasive in the known manner and this improved method has the characteristic feature that the grinding surface fails to show objectionable heating while grinding diamond facets and turning at more than three thousand revolutions per minute. A further advantage of this method of moving the gem is that the grinding track between the lines 16, 17 remains smooth and serviceable indefinitely and the formation of circular grooves in the grinding surface is entirely avoided. In previously known machines for facet grinding the gem remained fixed (or rotated about a self-contained axis) so that the grinding surface was soon grooved to such an extent that the grinding of flat facets became impossible.

Referring to Fig. 1 the dotted lines 20 indicate the outline of a gem that has been prepared by the formation of a table facet 21 and a culet 22 in readiness for the grinding of the facets.

The gem is then mounted in one of the holders or dopps in the manner hereinafter described and the machine is operated to grind and polish the facets 24 below the girdle line 23 after which another holder or dop receives the gem and is adjusted to the proper angle for the grinding and polishing of the facets 25 above the said line 23. The gem at Fig. 1 is shown with eight crown or bezel facets 25 and an equal number of pavilion or base facets 24, but it will of course be readily understood that the invention also applies to the formation of gems in which the upper facets comprise star facets, bezel or top main facets, top corner facets, and top half or break facets, while the lower facets comprise bottom half or break facets, bottom corner facets, and pavilion or bottom main facets, or to the formation of other shapes, styles, or types of gems or stones well-known in the lapidary art.

For the formation of the upper and lower facets the improved machine is preferably capable of adjustment for the grinding of facets of different angles, but the invention also contemplates the use of a series or battery of similar machines each adjusted to perform a different step or series or group of steps in the formation of the facets and also contemplates the formation of the various facets by two or more machines each incapable of adjustment for the grinding of more than a definitely limited group of facets, so that, for example, the facets 24 of Fig. 1 might be formed in one machine and the gem might then be transferred to another machine for the grinding of the facets 25.

The machine shown on the accompanying drawings is capable of adjustment and is provided with interchangeable parts whereby the various facets of the gem may be ground and polished without undue heating of the gem and without grooving, scoring, or otherwise defacing the surface of the grinding member, and the operations may be performed by operators of minimum skill and experience.

Referring to Fig. 3 the machine is made with a base 26 having an opening for the passage of a sleeve 27 which extends downwardly from a collar 28 suitably secured to the base (see also Fig. 4), and mounted in suitable bearings in the sleeve 27 is spindle 29. The ends of the spindle extend beyond the sleeve 27 and the upper end has the rotary grinding table 15 of iron or other suitable material secured thereto while the lower end of the spindle has secured thereon a belt pulley 30 adapted to be driven by an electric motor (not shown) so that the table 15 is rotated at the desired speed. Also mounted on the base 26 is a bracket 31 having a foot portion 32 secured to the base 26 and having an integral horizontal part 33 projecting over the table 15 and formed at its extremity with a vertically disposed sleeve part 34 having suitable bearings for a spindle 35 adapted to rotate about a vertical axis so that the gem 36 is moved in the path 19 as above described with reference to Fig. 2.

The spindle 35 rotates with an enclosing sleeve 37 to which it is suitably keyed and secured to the upper part of the said sleeve 37 is a belt pulley 38 driven from an electric motor (not shown, but preferably mounted upon the bracket 31). The spindle 35 is free to move axially within the sleeve 37 and downward movement is limited by engagement of the pulley 38 by a nut 39 engaging the upper screw-threaded portion of the spindle. The nut 39 has a lock nut 40 also mounted upon the spindle 35 and the distance between the nut 39 and the pulley 38 is thus capable of fine adjustment so that such distance may determine the exact depth of the grind or cut of the gem 36. The said nut 39 is formed with a groove 41 in its outer periphery for engagement by a stud 42 projecting from a rocking arm 43 pivoted at 44 on a projection 45 on the bracket part 33. One end 46 of the arm 43 forms a handle while the opposite end 47 has its upper edge shaped to form recesses 48, 49 for engagement by a stud 50 on the upper end of a lever arm 51 pivoted at 52 on an extension 53 on the bracket, and the lower end of the arm 51 is extended to form a handle 54 by means of which the stud 50 may be swung into position for engagement with the recess 49 after the handle 46 has been raised so as to lift the spindle 35 and the gem-carrying parts and thus stop the grinding or polishing operation. At the commencement of the operation the spindle 35

is set in motion and the handle 46 is first slightly raised and, while the handle 54 is swung to the right to disengage the stud 50 from the recess 49, the handle 46 is then moved slowly downwards to permit the weight of the gem-carrying parts to bring the gem into firm contact with the rotating surface of the table 15. The weight that gives the necessary grinding pressure is to some extent counterbalanced by the movable weight 55 adapted to slide along the arm 43 and having a set screw 56 by means of which it may be clamped in position for the desired pressure.

In order to provide a visual indication of the completion of each grinding operation the upper end of the spindle 35 is engaged by an adjustable set screw 57 screw-threaded through a socket in one arm of a double-armed lever 58 pivoted upon a portion 59 of the said extension 45 and having a spring 60 holding the screw 57 in engagement with the end of the spindle 35. The second arm of the lever 58 is capable of engaging a short projection 61 integral with a relatively long pivoted arm 62 having an indicating button 63 on its upper end. These parts form the visual indicator and are carried in a casing 64 mounted on the said extension 45. The casing 64 is provided with a sight slot 65 and has a spring 66 by means of which the indicator button 63 is normally held in the position shown.

When the grinding of the facet has been completed the nut 39 may rest upon the pulley 38 and the indicator button 63 is seen to vibrate in its slot 65. The operator then knows that the grinding has been completed, but he allows the machine to continue operating a little longer in order that the facet may receive a final polishing operation.

Referring now to the gem carrier and to the holders or dops, the lower end of the spindle 35 (see Figs. 3, 5, and 6) has clamped thereon a cross-head 67 having offset from the spindle axis an opening for a pivot pin 68 integral with a cylindrical casing 69 which is clamped by means of the nut 70 at an angle appropriate to the angle 45 of the facet to be ground, and a pointer 71 is mounted so as to swing with the casing 69 and to cooperate with a scale 72 to facilitate setting of the casing at the proper angle. The casing 69 serves as the carrier of the gem holders or dops which are adjustable and interchangeable and are each provided with means for gripping and holding the gem. In Figs. 3, 5, and 6 the casing 69 is shown carrying the dop designed to grip and hold the gem during the grinding of the base or pavilion facets, and this dop and its parts are shown at Figs. 7 and 8.

Referring to Figs. 3, 5, 6, 7, and 8, the dop for holding the gem during the grinding of the base or pavilion facets 24 (Fig. 1) is mounted in a sleeve 73 carried in the casing 69 and having at its upper end a collar 74 provided with suitably spaced peripheral recesses 75 for engagement by a hinged retainer 76 mounted on a pivot pin 77 on the casing 69 so that the sleeve 73 may be locked by the retainer 76 in different angular positions corresponding to the different facets 24. The recesses 75 correspond in number to the number of facets in the base or pavilion of the gem and while Figs. 3, 5, and 6 show collars with eight recesses corresponding to the facets of the gem shown at Fig. 1, a collar with sixteen recesses is shown at Fig. 8, and interchangeable collars may be provided to conveniently adapt the machine to the handling of gems of various designs. The sleeve 73 may be provided at its lower end

with nuts 78 to prevent axial movement and screws 79 or the like may also be provided for the purpose of tightening the casing 69 around the sleeve 73 to lock the latter against rotary movement when such locking is required. Fitted within the sleeve 73 is an inner tube 80 having its lower end (the left hand end Fig. 7) formed with an internal tapered or bevelled part 81 for engagement with a similarly tapered portion on a longitudinally split tubular part 82 whose slits 83 divide the projecting end into three segments forming jaws adapted to grip the gem as engagement with the tapered part 81 causes the said jaws to move inwardly. The said tubular part 82 is moved longitudinally for the closing of the jaws by the action of a sleeve member 84 having an actuating collar 85 and an externally screw-threaded portion for engagement with an internal screw-thread in the tube 80, and the latter is also screw-threaded externally for the reception of a washer 86 and nuts 87, and a latch device 88 on the collar 74 may be turned over the washer 86 to prevent relative movement of the parts in an axial direction. Centrally located in the dop is a stem 89 having screw thread engagement with the interior of the sleeve 84 and having an operating knob 90 and adjusting and locking nuts 91. The inner extremity of the stem 89 is socketed for the reception of one end of an interchangeable stem part 92 whose opposite end is formed with a flat face 107 accurately formed at right angles to the axis of the dop and adapted to press firmly against the table facet 21 (Fig. 1) of the gem so that the latter is maintained in proper position to ensure accurate angular disposition of facets being ground. During the grinding operation the dop is prevented from rotating about its own axis by the engagement of the hinged retainer 76 with one of the recesses 75 in the collar 74, while suitable splines or keys (not shown) prevent rotation of the tube 80 within the sleeve 73.

In the operation of the machine the gem is held at the desired angles to the grinding surface and is caused to turn in a circular path spaced a substantial distance from the center of rotation of the grinding table, and for the adjustment of the angle of the dop with respect to the grinding surface the dop may be so arranged that its longitudinal axis lies in a plane that is substantially tangential to the said circular path so that changes in such angle do not to any material extent increase or decrease the diameter of said path and the effective grinding surface or track upon the table thus remains substantially the same, and, since grooving and scoring are entirely avoided, the surface in question remains in practically permanent condition for satisfactory oper-

ation. In practice it has been found that, due to the constantly varying line of contact between the work and the grinding surface, the results are unusually satisfactory and the grinding surface is improved rather than deteriorated by long use.

Although the drawings and the above specification disclose the best mode in which I have contemplated embodying my invention, I desire to be in no way limited to the constructional details and arrangement of parts disclosed, for in the further practical application of my invention many changes may be made in the construction, arrangement, and dimensions thereof as circumstances require or experience suggests without departing from the spirit of the invention within the scope of the appended claim.

What I claim is:

20 A method of grinding and polishing gem facets which comprises rotating a flat annular lapping track about an axis at right angles thereto, holding the gem at an acute angle to said track during the lapping operation, preventing rotation of the gem about its own axis and rotating the gem 25 in contact with said track and in a circular path about a fixed axis parallel to said first axis, the diameter of said circular path being substantially equal to the width of the annular lapping track, said circular path being to one side of the first 30 axis, whereby the lapping action is applied to the gem at constantly varying angles with respect to the grain of the gem and whereby such grain is presented to the lapping track in parallel relation to the direction of movement of the contacting 35 portion of such track twice during each rotation of the gem in its circular path.

GREGOR H. RAKOWITZKY.
